UNITED STATES PATENT OFFICE

WINTHROP K. HOWE, OF ROCHESTER, NEW YORK, ASSIGNOR TO GENERAL RAILWAY SIGNAL COMPANY, OF ROCHESTER, NEW YORK

BRAKE SHOE FOR CAR RETARDERS

Original application filed November 21, 1925, Serial No. 70,599. Divided and this application filed June 12, 1926. Serial No. 115,562.

This invention relates to braking apparatus located along the track for retarding passing railway cars generally known as car retarders or track brakes, and more particularly to the brake shoes thereof and that portion of the track brake which facilitates quick and ready replacement of such brake shoes.

Car retarders of the track brake type, in which the cars are retarded by frictional resistance due to stationary brake shoes associated with the track gripping the sides of the car wheels, serve to retard all cars which pass through the same, and for this reason the brake shoes thereof are exposed to severe usage and require frequent replacement. In view of these considerations it is proposed in accordance with the present invention to construct the shoe beams on which the brake shoes are mounted, and these brake shoes, so as to constitute counter part structures of quick detachable inter-engaging means, whereby the brake shoes may be readily removed for replacement and the like. More particularly, it is proposed to construct the brake shoe so that a suitable bolt may be anchored therein, the various parts being so constructed that this anchoring between the bolt and the brake shoe is maintained so long as the bolt is in its normal fixed position.

Other objects, purposes and characteristic features of the invention will appear as the description thereof progresses.

In describing the invention in detail reference will be made to the accompanying drawings in which:

Fig. 1 shows a plan view of a portion of a car retarder of the track brake type more completely shown and described in the parent application hereinafter referred to;

Fig. 2 is a sectional elevation taken on the line 2—2 of Fig. 1;

Fig. 3 illustrates how the steel insert is cast into the brake shoe, this view being taken on the line 3—3 of Fig. 2;

Fig. 4 is a vertical cross-section taken crosswise through the shoe beam and the brake shoe illustrating the manner of attachment of the brake shoe, and taken on the line 4—4 of Fig. 3; and

Fig. 5 is a horizontal cross-section of the

shoe beam and brake shoe also illustrating the manner of attachment of these parts.

This application is a division of my prior application Ser. No. 70,599, filed November 21, 1925.

Referring to the drawings, a portion of a railway track comprising a rail 1 secured to ties 2 through the medium of guide blocks 3, more particularly shown in Fig. 2 has been illustrated. The various ties 2 are fastened together by an angle bar 4 extending along one end of the ties, and a bar of strap iron 5 extending along an intermediate point of the ties, these bars or straps being fastened to the ties by lag screws 7, as shown. Parallel to the angle bar 4 and spaced a suitable distance above the same, is a bearing piece 10 which, in connection with the angle bar 4, forms journals for pins 11 of the various double angle levers 12, these angle levers being pivotally supported on the pins 11 and through the medium of pins 13 and 14 are adapted to move the girder beams 17 and 18 in opposite directions as the double angle levers are moved in a certain direction. These girder beams 17 and 18 are of identical construction, and each include an upwardly and sidewardly projecting apertured lug 17^a and 18^a and in the construction illustrated, are arranged so that these lugs are on opposite ends of the parallelly arranged girders 17 and 18. Referring to Fig. 2, the right hand ends of the girder beams 17 and 18 rest on the strap 5 and are held against transverse movement by a U-shaped girder beam guide 20. This girder beam guide is of such width that it may accommodate the free ends of girder beams 21 and 22 which extend underneath the other rail (not shown) of the trackway, the opposite ends of the girder beams 21 and 22 being supported in the girder beam guide similar to the one shown. It should be noted that the right hand ends of girder beams 21 and 22 are spaced apart in the girder beam guide and that the girder beams 17 and 18 are operatively connected to the girder beams 21 and 22 by links 28 and 29, respectively. From the construction thus far described, it appears that if the double angle lever 12 (see Fig. 1) is moved upwardly, that the lug 100

17^a moves toward the left and the lug 18^a moves toward the right; in other words, the lugs projecting from adjacent girder beams move toward each other as the double angle lever is moved to a higher braking position. Since the various groups of angle levers and associated mechanisms are the same, they may be assigned like reference characters having distinctive exponents. The various 10 double angle levers 12 are connected together by a main operating beam 30. Referring to Fig. 2, it will be noted that the guide blocks 3 on opposite sides of the rail 1 are of identical construction and that they provide, in a 15 manner shown and described in the parent application, a slidable engagement between the shoe beams 33 and the guide blocks 3, thus permitting independent lateral movement of the shoe beams 33, but not permitting 20 rolling movement of these shoe beams 33. In this connection an adjoining pair of these blocks 3 may be cast integral, if desired, in which event they will be passed over the end 25 of the rail during assembling.

It should be noted that one shoe beam 33 is provided for every two double angle levers 12 and that one end of these shoe beams is provided with a vertically disposed slot into 30 which the adjoining end of another shoe beam having a projecting tongue which snugly fits this slot, is adapted to engage; in other words, each shoe beam has a vertical slot on one end and a vertically disposed tongue on the other and the tongue of each shoe beam 35 engages the slot of its adjoining shoe beam. This articulates the connection between adjacent shoe beams thus affording what may be said to be a continuous flexible braking surface. Referring to Fig. 2, it will be noted 40 that a spring guide 35 is connected pivotally by a pin 36 between flanges projecting from the shoe beam 33 and that the free end of this spring guide 35 extends through the perforation of a lug projecting from one of the 45 girder beams, such, for instance, as the lug 18^a projecting from the girder beam 18 shown in Fig. 3. This spring guide 35 is threaded at its free end and carries a nut 37 and a lock nut 38 whereby the spacing between the shoe beams for any particular retarder position 50 may be determined. On this spring guide 35 is carried an initially tensioned coil spring 40, the initial tension of which may be adjusted by the initial tension variable spacer 55 comprising the threaded bushing 41 and the nut 42 threaded thereon. It readily appears that the minimum or initial tension to which the spring 40 is compressed is determined by this spacing bushing 41 and nut 42 after the 60 nuts 37 and 38 have once been adjusted; so that not only can the spacing between the brake shoe beams 33 be fixed, but the initial or minimum tension of the spring 40 may be adjusted to any desired value.

For reasons obvious to those skilled in the

art of braking, a certain amount of wear on the brake shoes is experienced in consequence of which it is necessary to replace brake shoes from time to time, and for this reason the brake shoes 45, two in number for the particular embodiment shown, are detachably secured to each of the brake shoe beams 33. In the particular construction shown, referring to Figs. 3, 4 and 5, the brake shoe 45 is provided with a steel insert 46, which insert 70 is placed in the mould and cast integral with the shoe 45, the cast iron employed being of a composition generally used in brake shoes on freight cars which has all of the desired characteristics, such as, toughness, flexibility 75 and coefficient of friction. In order to effect a substantial connection between the brake shoe 45 and its steel insert 46, this insert 46 is perforated as shown at 47, so that the molten iron will flow into these perforations, 80 and upon cooling and contracting, it will firmly connect the insert to the brake shoe. By looking at Fig. 1 it will be noted that the brake shoes 45 are arranged end to end in a 85 manner so that endwise movement of a single shoe is permitted only to a very slight extent, and that very little clearance between the shoe beam 33 and the rail 1 is present so that special securing means is necessary to hold the shoe 45 in position in a manner so that 90 any one of the brake shoes may be removed separately without removing adjoining brake shoes. In the particular embodiment illustrated, this is accomplished by having the insert 46 provided with elongated longitudinally arranged slots 48, each of which slots 95 is adapted to allow the T-shaped head 49 of the bolt 50 to pass therethrough, a cavity of sufficient size being left in the casting of the 100 brake shoe 45 to allow this T-shaped head 49 to be turned through an angle of 90°, as clearly shown in Fig. 3. The main portion of the bolt 50 is circular in cross-section, but a small portion of this bolt adjacent the head 49 is square, and this square portion of the 105 bolt fits in a square opening in the shoe beam 33, so as to hold the bolt from turning as its nut 51 is tightened and also to keep the T-shaped head 49 from turning and disengaging 110 the brake shoe. From this construction 115 it will readily appear that if the nut 51 is loosened and backed off, the bolt 50 may be pushed inwardly until the square portion thereof has passed out of the square opening 120 in the shoe beam 33, whereupon the bolt 50 may be turned through an angle of substantially 125 90° and the brake shoe may be slipped off by allowing the T-shaped head to pass 130 through the slot 48. To facilitate turning of the bolt 50, a transverse hole is preferably 135 drilled near its outer end to receive a suitable pin 52 (see Fig. 4), or other tool, by means of which the bolt can be easily turned. Also, it should be noted that the brake shoe 45 has cast integral therewith a projecting 140

lip 53 which engages a longitudinally arranged groove contained in the brake shoe beam 33. This engagement of the lip 53 with this groove to a large extent relieves the bolt 50 of vertically as well as horizontally acting shearing stresses.

By reason of the construction of the brake shoes and the shoe beams described, there is provided a quick detachable connection between the shoes and the shoe beams which maintains the shoes against displacement by the force acting upon them in the use of the retarder, but also permits ready removal and replacement of the shoes as they become damaged or worn. It should be noted that the brake shoes are arranged longitudinally in a row end to end, so that endwise movement of the brake shoes can not be utilized to provide for engagement or disengagement as a means for attaching the shoes to the shoe beams. Likewise, the disposition of the brake shoes with relation to the track rail allows only a limited amount of movement of the brake shoes away from the shoe beams toward the rails. It is important, therefore, that the shoe attaching means should be of such character that it may be engaged and disengaged without endwise movement of the shoe, and with a limited amount of side-wise movement toward the track rail. Also, on account of exposure to the rubbing action of the wheels, it is desirable to maintain the surface of the brake shoe uniform and uninterrupted, so that a further desirable limitation of the shoe attaching means is that it should connect to the back face of the brake shoe, i. e., the face next to the shoe beam. The shoe attaching means of this invention, including obvious variations and modifications of the particular structure shown, satisfies these practical requirements and limitations.

Having thus shown and described one particular form of the invention and how it is performed, it is desired to be understood that the particular construction shown and described does not exhaust all possible forms of means for carrying out the functions within the scope of the present invention, and that various changes and modifications may be made without departing from the scope of the invention or the ideas of means underlying the same.

What I claim as new and desire to secure by Letters Patent is:—

1. A readily detachable brake shoe for car retarders of the type in which brake shoes frictionally engage the sides of car wheels, and in which shoe beams have holes therein of non-circular configuration, each hole of which contains a bolt having a T-shaped head, the body of said bolt being generally round but having the portion normally contained in such hole formed to have a corresponding non-circular configuration comprising, a brake shoe having a slot allowing

said T-shaped head to pass therethrough, but which will not allow said head to pass therethrough if said bolt has been turned through an angle of substantially 90°, whereby said brake shoe may be removed if said bolt is moved out far enough to bring the parts of non-circular configuration out of cooperative relation with its shoe beam hole and the bolt is turned to bring the T-shaped head into registration with the slot in the brake shoe. 70

2. A brake shoe for car retarders of the track brake type comprising, an oblong member consisting of a casting having a steel plate insert cast integral therewith, said steel insert being flat and forming the back of said brake shoe so that the brake shoe will firmly rest against a flat shoe beam for supporting the same, the insert having oblong openings therein arranged lengthwise in said insert and in alignment with each other, said castings having recesses molded therein to provide sockets for T-headed bolts the heads of which may pass through said openings when assuming a certain angular position but which heads will not pass through said openings if the bolts assume another angular position. 75

3. A brake shoe for car retarders of the type in which brake shoes frictionally engage the sides of passing car wheels comprising, an elongated bar of cast metal having recesses cast into the back thereof and having a flat steel plate insert cast into the back thereof, said steel plate being so shaped that upon cooling of the casting said steel plate is firmly anchored thereto and forms an integral part thereof, said plate having slots therein arranged longitudinally of said elongated bar and each located over one of said recesses, said recesses permitting bolts having T-shaped heads to pass therethrough if in one position but not allowing such heads to pass therethrough if in another position, whereby the complete brake shoe structure may be anchored to a suitable shoe beam. 100

4. A brake shoe for car retarders of the type in which brake shoes frictionally engage the sides of passing car wheels comprising, an elongated bar of cast metal having recesses cast into the back thereof and having a flat steel plate insert cast into the back thereof, said steel plate being so shaped that upon cooling of the casting it is firmly anchored thereto and forms an integral part thereof, said plate having slots therein arranged longitudinally of said elongated bar and each located over one of said recesses, said recesses receiving bolts having T-shaped heads and a body portion of non-circular configuration, the heads passing through said slots if turned in one position but not if turned in another position, whereby the complete brake shoe structure may be anchored to a suitable shoe beam containing holes of similar non-circular configuration for receiving said bolts, said 115

bolts when in their normal position having their non-circular portions contained in the non-circular holes by said bolts and if partly retracted permitting the T-shaped heads to be turned to disengage said slots.

5. Means for frictionally engaging the side of a car wheel comprising, a shoe beam arranged longitudinally along a track rail of a railway track including a vertically disposed web having holes therein, a brake shoe having slots and recesses in its rear face to register with the holes in the shoe beam, and anchoring members having T-shaped heads which may pass through the slots in the brake shoe if in one angular position but which will not pass therethrough when in a different angular position, said anchoring members passing through the holes in the shoe beam, means associated with the anchoring members to facilitate turning them, and means for moving said anchoring members endwise to clamp the shoe against the shoe beam.

6. In a car retarder, the combination with a shoe beam and a brake shoe having faces and edges supported thereby, of fastening elements passing through said shoe beam and having a separable attachment to the rear face of said shoe, said fastening elements being disengageable from the shoe without edgewise movement of said shoe.

7. In a car retarder, in combination a shoe beam extending along the track rail, a brake shoe on the front face of said beam, and fastening means for said shoe passing through said beam from the rear, and means connecting said fastening means to the rear face of the shoe and permitting detachment therefrom without endwise movement of the shoe.

8. A brake shoe of the character described attachable and detachable with relation to a shoe beam without requiring endwise movement of the shoe, comprising a block of cast metal reinforced at its back by a steel plate, said plate and block being formed with means for securing a fastening element to the rear of the shoe without the relative displacement of the shoe and said fastening element in a direction lengthwise of the shoe.

9. A brake shoe of the character described comprising, a rectangular block of friction material formed with two longitudinally spaced recesses and slots in one face, said slots being adapted to admit the head of a fastening member, said recesses being shaped to permit turning of said fastening member through an angle to thus retain it in place.

10. In a car retarder, in combination, a shoe beam, a brake shoe having a socket in its inner face, a rectangularly slotted plate cast into the inner face of the brake shoe with its slot over said socket, and a rectangularly headed bolt, receivable through said slot and into said socket, only when in one angular position of the bolt, detachably connecting the shoe to the beam.

11. In a car retarder, in combination, a shoe beam, a brake shoe having a socket in its inner face, a rectangularly slotted plate cast into the inner face of the brake shoe with its slot over said socket, and a rectangularly headed bolt, receivable through said slot and into said socket, only when in one angular position of the bolt, passing through a non-circular opening in the shoe beam, the shank of the bolt, for but a short distance adjacent its head, being shaped to match said non-circular opening, whereby to detachably connect the shoe to the beam.

12. In a car retarder, in combination, a shoe beam, a brake shoe having a socket in its inner face, a rectangularly slotted plate cast into the inner face of the brake shoe with its slot over said socket, and a rectangularly headed bolt, receivable through said slot and into said socket, only when in one angular position of the bolt, passing through a non-circular opening in the shoe beam, the shank of the bolt, for but a short distance adjacent its head, being shaped to match said non-circular opening, whereby to detachably connect the shoe to the beam, means to cause the bolt to draw the shoe and beam together and matching tongue and groove means in the shoe and beam to prevent relative movement therebetween when the shoe is drawn against the beam.

13. A brake shoe for car retarders of the track brake type, comprising, a cast metal shoe, pockets in the rear face of the shoe, a steel insert secured in the rear face of the shoe and having slots positioned over the said pockets, said slots and pockets being symmetrically positioned in the shoe, whereby to permit the shoe to be used when reversed, end for end, and top for bottom.

14. A brake shoe of friction material, formed with an inner recess and a connecting slot in one face of the shoe, said slot being shaped to admit the head of a fastening member, and said recess being shaped to permit turning of said fastening member through an angle to thus retain it in place.

15. In a car retarder, in combination, a brake shoe having a socket inwardly of its inner face, a rectangular slot in the inner face of said brake shoe positioned over, and connected with, said socket, and a rectangularly headed bolt receivable through said slot and into said socket only when in one angular position of the bolt, and rotatable within said socket, for detachably connecting the shoe to a carrier member.

16. For use in a car retarder, a brake shoe, one face of said shoe having a rectangular slot therein, and an inner socket in the shoe connected to said slot and having its smallest dimension parallel to said one face at least substantially equal to the length of said rectangular slot, whereby to furnish connecting means for said shoe.

17. For use in a car retarder, a brake shoe, one face of said shoe having a rectangular slot therein, and an inner socket in the shoe connected to said slot and having its smallest dimension parallel to said one face at least substantially equal to the length of said rectangular slot, whereby to furnish connecting means for said shoe and a retaining tongue on said shoe projecting beyond said face of said shoe.

18. A brake shoe for car retarders of the track brake type, comprising, a block of friction material, pockets inwardly of the rear face of the block, slots in the rear face of the block positioned over and connected with the said pockets, said slots and pockets being symmetrically positioned in the shoe, whereby to permit the shoe to be used when reversed, end for end, and top for bottom.

20 In testimony whereof I affix my signature.
